UNITED STATES PATENT OFFICE.

CASPER F. HANSON, OF ALBERT LEA, MINNESOTA, ASSIGNOR TO OLSON MANUFACTURING COMPANY, OF ALBERT LEA, MINNESOTA, A CORPORATION OF MINNESOTA.

CONVEYING APPARATUS.

Application filed May 16, 1928. Serial No. 278,079.

My present invention has for its object the provision of a relatively simple conveying apparatus intended for general use, but especially adapted for use in connection with litter carriers of the type used in barns. As is well known, horizontal swinging cranes are now commonly used for carrying sections of tracks for such litter carriers outside of the barn where the litter may be dumped over a relatively large area and at a distance from the barn. Such cranes place a great deal of strain on a barn structure and the length of the track section that can thus be carried by a crane is limited to the strain that a barn structure will stand and the elevation above the crane to which one or more supporting members therefor may be attached. As a great many barns are of the shed type, it is very difficult and often impossible to mount a crane of this type thereon.

The invention includes a structure in which a horizontal swinging crane may be supported in such a manner as to relieve a barn structure of substantially all strain and it is well adapted for use in connection with barns of the shed type in which there is very little space above the door opening through which the litter carrier travels to and from the barn.

This conveying apparatus also materially increases the distance a litter carrier may be conveyed from a barn.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a view showing a fragment of a barn structure in vertical section and also illustrating the invention diagrammatically;

Fig. 2 is a view of the mast with the bridge sectioned on the line 2—2 of Fig. 1;

Fig. 3 is a plan view of the mast and crane and also showing a portion of the bridge;

Fig. 4 is a fragmentary view partly in side elevation and partly in section of the parts shown in Fig. 1;

Fig. 5 is a plan view of the sections of the

cross member of the mast and adjacent portions of the track sections and bridge; 55

Fig. 6 is a fragmentary plan view of the strut and crane as shown in Fig. 4; and

Fig. 7 is a detail view partly in elevation and partly in section taken on the line 7—7 of Fig. 4, on an enlarged scale. 60

The numeral 8 indicates a barn structure having in its lower floor a door opening 9 over which is a heavy header 10 and which door opening opens onto a barnyard 11. On the lower floor of the barn 8 is a litter 65 carrier track 12 which leads to the door opening 9.

Referring now in detail to the invention the numeral 13 indicates an A-shaped mast spaced from the barn 8 and set flatwise parallel to the side of said barn having the door opening 9 and directly in front of said door opening. The cross member of the mast 13 comprises a pair of timbers 14 and 15 secured one to each face of said mast. The 75 legs of the mast 13 rest on concrete piers 16 having embedded therein anchor straps 17 bolted to said legs and rigidly holding said mast in place.

A fixed track section 18 forms a continuation of the track section 12 and extends to the mast 13 and a horizontal swinging track section 19 extends outward of said mast, forms a continuation of the track section 18 and is attached thereto by a short flexible 85 track section 20 which permits horizontal swinging movement of said track section 19. The track section 18 is suspended by a plurality of hangers 21 from a bridge 22 in the form of a beam comprising rigidly connected 90 longitudinally aligned tubular sections. One end of the bridge 22 is rigidly secured to the header 10 by a coupler 23 and the other end thereof is rigidly secured by a coupler 24 to the mast section 14. Each coupler 23—24 is 95 vertically longitudinally divided and the sections thereof are rigidly connected by upper and lower draw-bolts which frictionally clamp the sections of each coupler 23—24 onto the bridge 22.

The sections of the coupler 23 have integrally formed therewith laterally and horizontally extended flanges 25 which bear directly against the outer face of the barn 8 in front of the header 10 and are rigidly 105 bolted to said barn and header, as best shown

in Fig. 4. The coupler 24 is also provided with laterally and horizontally extended flanges 26 which bear against the barn side of the mast section 14 and are rigidly bolted thereto.

A pair of diverging brace irons 27 rigidly secure the track section 18 to the mast section 14 and hold said track section 20 against lateral movement during horizontal swinging movement of the track section 19 or when said track section is in a position out of alignment with the track section 18. A plurality of intermediate couplers 28 are applied to the bridge 22 at longitudinally spaced points and each thereof is vertically and longitudinally divided and the sections thereof connected by draw-bolts which frictionally clamp said sections onto the bridge 22.

20 A pair of horizontally aligned tubular struts 29 extend transversely from opposite sides of the bridge 22 and are rigidly secured to the couplers 28 by having their inner end portions mounted in sockets in said couplers 25 and frictionally held in position.

As shown, there are three pairs of struts 29 and the intermediate pair are somewhat longer than the end pairs thereof. Guy wires 30 have their ends anchored in eyes on the sides of the couplers 23 and 24 and their intermediate portions extend through holes in the struts 29 near their outer ends. A turn buckle 31 is interposed in each guy wire 30 for holding the same taut. Obviously the struts 29 and guy wires 30 securely hold and brace the bridge 22 against lateral buckling movement.

The track section 19 is carried by a crane 32 comprising a beam made up of longitudinally aligned tubular sections similar to the bridge 22. The crane 32 is connected to the mast section 15 by a hinge 33 for horizontal swinging movement. This crane 32 may be brought into longitudinal alignment with the bridge 22 or swung laterally to either side of this position.

The anchor member of the hinge 33 is rigidly bolted to the mast section 15. On the outer end of the crane 32 is a coupler 34 that is longitudinally and vertically divided and the sections thereof connected by draw-bolts which frictionally clamp said coupler onto the crane 32.

Couplers 35 similar to the couplers 28 are applied to the crane 32 at longitudinally spaced points and struts 36 in the same arrangement as the struts 29 are secured to said couplers 35. A pair of guy wires 37 have their ends anchored to the eyes on the sides of the movable member of the hinge 33 and the coupler 34 and their intermediate portions are extended through holes in the struts 36 near the outer ends thereof. A turn buckle 38 is interposed in each guy wire 27. The struts 36 and guy wires 37 for the crane

32 serve the same purpose as the struts 29 and guy wires 30 for the bridge 22.

The bridge 22 and crane 32 are supported in substantially balanced relation from the top of the mast 13, the former by a group 70 of supporting members 39 and the latter by a group of supporting members 40. The supporting members 39 and 40 are in the form of wire cables and one of the ends of the supporting members 39 are secured in a single eye-bolt 41 in the top of the mast 13 and projecting from the barn side thereof and their lower ends are connected by turn buckles 42, the one to an eye in the top of the coupler 23 and the others to eyes on the 75 tops of the couplers 28. It will thus be seen that the support members 39 extend in diverging relation from the top of the mast 13 and support the bridge 22 at longitudinally spaced points.

The supporting members 40 are identical with the supporting members 39 and have one of their ends attached to an eye 43 in the bolt 41, on the opposite side of the mast 13 from the barn 8.

Turn buckles 44 connect the lower ends of the supporting members 40, the one to an eye on the top of the coupler 34 and the others to eyes on the tops of the couplers 35. These supporting members 40 also extend 95 in diverging relation from the top of the mast 13 but on the opposite side thereof from the supporting members 39 and support the crane 32 at longitudinally spaced points.

It is important to note that the eye 43 is located directly over the pivot member of the hinge 33 and that the flexible track section 29 is directly below the hinge 33 so that the track section 19, crane 32 and supporting members 40 are held for horizontal swinging movement about a common vertical axis.

By supporting the track 22 and crane 32 from an intermediate point in substantially balanced relation, substantially all strain is removed from the barn structure 8 and only a relatively light upward strain is placed on the header 10 by the crane 32 and parts carried thereby.

What I claim is:

1. An apparatus of the class described comprising an upright mast, a bridge having one of its ends attached to the mast and having at its other end means for attaching the same to a support, a supporting member anchored to the mast above the bridge and attached to the bridge at a distant point from the mast for supporting said bridge from the mast, a crane mounted on the mast and forming an extension of the bridge, and a track carried by the bridge and crane.

2. An apparatus of the class described comprising an upright mast, a bridge having one of its ends attached to the mast and

having at its other end means for attaching the same to a support, a plurality of supporting members anchored to the mast above the bridge, extending downwardly 5 and outwardly therefrom in diverging relation and attached to the bridge at longitudinally spaced points and supporting the same from the mast, a crane mounted on the bridge and forming an extension of the 10 bridge, and a track carried by the bridge and crane.

3. An apparatus of the class described comprising an upright mast, a bridge having one of its ends attached to the mast and 15 having at its other end means for attaching the same to a support, a crane hinged to the mast for horizontal swinging movement and forming an extension of the bridge, reversely extended supporting members anchored to the mast above the bridge and 20 crane, attached to said bridge and crane and supporting the same from the mast in substantially balanced relation, and a track carried by the bridge and crane.

25 4. An apparatus of the class described comprising an upright mast, a bridge having one of its ends attached to the mast, a supporting member anchored to the mast above the bridge and attached to the other end 30 of the bridge, said other end of the bridge having means for attaching the same to a support, a crane hinged to the mast for horizontal swinging movement and forming an extension of the bridge, a second supporting 35 member anchored to the mast above the hinged end of the crane and attached to the outer end of the crane, and a track carried by the bridge and crane.

5. An apparatus of the class described 40 comprising an upright mast, a bridge having one of its ends attached to the mast, a supporting member anchored to the mast above the bridge and attached to the other end of the bridge, said other end of the bridge 45 having means for attaching the same to a support, a crane hinged to the mast for horizontal swinging movement and forming an extension of the bridge, a second supporting member anchored to the mast above 50 the hinged end of the crane and attached to the outer end of the crane, track sections carried by the bridge and crane, and a flexible track section connecting said track section at the mast.

55 6. An apparatus of the class described

comprising a fixed A-mast, a bridge having one of its ends attached to the cross member of the mast and projecting from one side thereof, a supporting member anchored to the mast above the bridge and attached to the other end of the bridge, said other end of the bridge having means for attaching the same to a support, a crane hinged to said cross member for horizontal swinging movement and forming an extension of the 65 bridge, a second supporting member anchored to the mast above the hinged end of the crane and attached to the outer end of the crane, and a track carried by the bridge and crane. 70

7. An apparatus of the class described comprising a mast, a bridge having one of its ends attached to the mast, a plurality of supporting members anchored to the mast above the bridge and attached to the bridge 75 at longitudinally spaced points, said other end of the bridge having means for attaching the same to a support, a crane hinged to the mast for horizontal swinging movement and forming an extension of the bridge, a plurality of other supporting members anchored to the mast above the hinged end of the crane and attached to the crane at longitudinally spaced points, and a track carried by the bridge and crane. 85

8. An apparatus of the class described comprising a mast, a bridge having one of its ends attached to the mast, means at the other end of the bridge for attaching the same to a support, said bridge comprising a 90 beam and a plurality of transverse struts having intermediate couplings attaching the same to said beam at longitudinally spaced points, a pair of guy wires anchored to the ends of the beam and held in the ends of the 95 struts, a crane hinged to the mast for horizontal swinging movement and forming an extension of the bridge, said crane comprising a beam arranged to be brought into longitudinal alignment with the beam of the 100 bridge, a plurality of other transverse struts having intermediate couplings attaching the same to the beam of the crane at longitudinally spaced points, supporting members anchored to the mast above the bridge and 105 crane and attached to the couplings of the struts on said two beams.

In testimony whereof I affix my signature.

CASPER F. HANSON.
